UNITED STATES PATENT OFFICE.

BERTRAND J. HORTON, OF PAWTUCKET, RHODE ISLAND.

NECKTIE-FASTENER.

SPECIFICATION forming part of Letters Patent No. 283,889, dated August 28, 1883.

Application filed May 14, 1883. (No model.)

To all whom it may concern:

Be it known that I, BERTRAND J. HORTON, of Pawtucket, in the county of Providence and State of Rhode Island, have invented a new and useful Improvement in Necktie-Fasteners; and I hereby declare the following to be a full, clear, and exact description of the same, reference being had to the accompanying drawings, forming part of this specification.

This invention has reference to an improvement in means for securing a necktie to the collars of shirts; and it consists in a stem secured to the necktie and a collar-button constructed to receive the stem, so as to secure the necktie, as will be more fully set forth hereinafter.

Figure 1 is a view of my improved collar-button and necktie-fastener, and also a transverse sectional view of the shank of the collar-button. Fig. 2 is an end view of the collar-button. Fig. 3 is a sectional view of the collar-button, showing the necktie-fastener secured therein. Fig. 4 is a view of the collar-button and necktie-fastener, showing the fastener secured to the necktie by the bending of the fastening-strip. Fig. 5 is a view of the collar-button and necktie, showing the fastener secured by a double strip bent into and fastened to the necktie. Fig. 6 is a view of a collar secured by the collar-button. Fig. 7 is a view of a collar and a necktie secured thereto, (shown in solid lines and in broken lines,) indicating the position of the necktie when the stem is inserted into the collar-button.

In the drawings, *a* is the oval shank of the collar-button made of this flattened shape, so that it will be held against turning in the button-holes of the shirt-band and the collar. *b* is an oblong hole made in the collar-button to receive the stem of the necktie-fastener.

c is the head of the collar-button.

d is the shoe of the same.

e is the stem of the necktie-fastener, and *f* is the enlarged head of the same. The stem and end are made so as to enter the hole *b*, and by partly turning the same to secure the stem in the collar-button, as is shown in Figs. 2 and 3.

g is a disk to which the stem *e* is secured, and *h* is a strip which is inserted in the material of the necktie, and is bent so as to firmly secure the stem *e* to the necktie, as is shown in Fig. 4. The strip *h* may form a double strip, pointed to enter the material of the necktie, so that the same can be secured, as is shown in Fig. 5.

I is the band of a collar, having the collar-button secured in the button-holes.

I' is one point of a turn-down collar, and *I''* is the other point of the same.

K is the necktie, which may be of any form, shape, or design.

The stem *e* having been firmly secured to the necktie by means of the strip or strips *h*, so that the disk *g* rests against the necktie, when now the necktie is placed at right angle to the position it is to permanently occupy, the stem *e* can be inserted into the flattened hole *b* of the collar-button, and when entered the necktie can be placed in the desired position by turning the stem *e* in the hole, and thereby firmly securing the same, and when a turn-down collar is used one end of the necktie can be entered under the point *I''*, and then the other under the point *I'*, and the necktie will be firmly held in place.

By the use of my improved collar-button and necktie-fastener the necktie can be quickly and firmly secured and permanently held in place. It can with the same facility be removed, forming a convenient article.

I do not wish to confine myself to the exact construction shown and described, as various modifications may be made to combine a collar-button and necktie-fastener which will produce practically the same result.

Having thus described my invention, I claim as new and desire to secure by Letters Patent—

The combination, with the flattened shank *a*, the head *c*, and shoe *d* of a collar-button provided with an elongated hole, of the stem *e*, disk *g*, and strip *h*, constructed to secure the stem to the necktie and the necktie to the collar-button, as described.

BERTRAND J. HORTON.
